(57) **CLAIM**

The ornamental design for a hinge plate adapter, as shown and described.

DESCRIPTION

FIG. 1 is a side perspective view of the hinge plate adapter showing my new design at a reduced scale and installed on a hinge plate and guitar body which are shown in broken lines; FIG. 2 is a back perspective view of the hinge plate adapter; FIG. 3 is a front perspective view of the hinge plate adapter; FIG. 4 is a front plan view of the hinge plate adapter; FIG. 5 is a back plan view of the hinge plate adapter; FIG. 6 is a top view of the hinge plate adapter with the bottom view being a mirror image; and, FIG. 7 is a left side view of the hinge plate adapter with the right side being a mirror image. The broken lines are included for the purpose of showing the environment of use and form no part of the claim.
